(57) **CLAIM**

The ornamental design for a pocket binder sheet, as shown and described.

DESCRIPTION

FIG. 1 is a perspective view of a pocket binder sheet showing my new design;

FIG. 2 is a front elevation view thereof;

FIG. 3 is a back elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a perspective view of the pocket binder sheet of FIG. 1 as it would be positioned during use;

FIG. 9 is an enlarged view of the encircled portion in FIG. 4; and,

FIG. 10 is an enlarged view of the encircled portion in FIG. 5.

The dash-dot lines in FIGS. 4, 5, 9 and 10 illustrate the boundaries of the enlarged view indicators and form no part of the claimed design.

1 Claim, 10 Drawing Sheets
